ANNUNCIATING AND INDICATING APPARATUS

Arthur P. Jackel, Penn Township, Allegheny County, Pa., assignor to The Union Switch & Signal Company, Swissvale, Pa., a corporation of Pennsylvania

Application November 25, 1943, Serial No. 511,695

9 Claims. (Cl. 177—353)

My invention relates to annunciating and indicating apparatus, and is suitable for use in centralized traffic control systems for railroads to provide continuously visible and momentarily audible indications of traffic conditions at remote points.

In systems of this character, a miniature track diagram is generally provided at the control office, comprising a representation of the track layout with the tracks of the diagram illuminated by lamps controlled by indication relays which reflect the condition of the corresponding track sections. These may include approach indication lamps, each lighted to indicate that a train has entered an approach zone, and track indication lamps each lighted when a train occupies a detector section including an interlocked track switch. Since the number of lamps is usually quite large it is of advantage to provide an audible signal device to attract the operator's attention promptly to the display of a new approach indication on the track diagram, and under some conditions to cause the signal to sound again when the approaching train enters a detector track section.

One object of my invention is to provide indicating and annunciating apparatus of this character which is suitable for use in systems employing quick acting indication relays, such as those of the stick polar type as shown, for example, in Letters Patent of the United States No. 2,140,604, issued December 20, 1938, to Clarence S. Snavely, for Electrical relays, to which the circuits used heretofore in connection with relays of other types are not applicable.

A further object of my invention is to provide improved circuits for controlling an audible signal device by a large number of indication relays using only one contact finger on each indication relay and only one additional relay, employing indication relays having standard windings and contact adjustments and identical with those used elsewhere in the system.

I shall describe one form of apparatus embodying my invention, and shall then point out the novel features thereof in claims.

Referring to the accompanying drawing, to illustrate my invention I have shown three stick polar indication relays and suitable circuits therefor, these being the relays TK, RAK and LAK. It is to be understood that in general the centralized traffic control system employs a large number of such relays, and that each is adapted to operate its contacts *a* and *b* to the left-hand or normal position, as shown, when current from the positive terminal of a suitable source flows from left to right through its winding, and to operate its contacts to the right-hand or reverse position in response to current flowing in the opposite direction, and that the contacts are held

magnetically in their last operated position when the relay is deenergized. A battery having a positive terminal *B*, a negative terminal *C*, and a center tap or intermediate terminal *O*, provides current for reversibly energizing the relays. The reverse contact *a* of each relay controls a correspondingly designated lamp *E* in the track diagram, as shown, while the normal and reverse contacts *b* are all connected in series in a circuit controlling an additional relay *XR*, which, as shown, is a biased polar relay of a sensitive type arranged to close its reverse contacts when deenergized, as indicated conventionally by biasing springs on its contacts.

Contact *d* of relay *XR* controls the audible signal device illustrated as a single stroke bell *XB*.

The remote control system by which the indication relays are controlled may be of any suitable type, the one chosen to illustrate my invention being that of Letters Patent of the United States No. 2,292,245, issued August 4, 1942, to Clarence S. Snavely, Alfred B. Miller and Arthur P. Jackel, the relays shown herein corresponding in function to the similarly designated relays of this patent.

For an understanding of my invention it is deemed sufficient to point out that the remote control system includes an office receiver responsive to indication codes comprising a series of spaced impulses for operating a chain of stepping relays including the relays *IP*, *10P*, *12P* and *14P*, one at a time on the correspondingly numbered steps, and that the character of each impulse is made manifest by the energization of one or the other of two character determining relays *A2* and *C2*. As shown, steps 10, 12 and 14 of the code are assigned to the control of relays *TK*, *RAK* and *LAK*, respectively, each of which is operated to normal or reverse depending on whether relay *A2* or *C2* is picked up when the corresponding relay *P* is operated. Relay *A1* is a normally energized relay which is released for the duration of each code. Relay *OR* responds selectively to the character of the first step, and conditions the apparatus to function as a receiver, since as explained in the patent, the same coding apparatus functions at times as a code transmitter.

On the first step of a received code, relay *A1* releases and relays *A2* and *IP* pick up, completing a circuit from terminal *B* at contact *e* of relay *A2* over contact *c* of relay *IP* through relay *OR* to terminal *C*, so that relay *OR* picks up completing a stick circuit over its own contact *a* extending to terminal *B* at contact *b* of relay *A1* whereby relay *OR* is held energized until the end of the code. On the first step, before relay *IP* releases, relay *OR* completes a pick-up circuit for relay *XR* from terminal *B* at its contact *e* over contact *c* of relay *IP*, resistor *20* and the

upper winding of relay XR to terminal C, operating relay XR to close its contact *a* and to open its contacts *b* and *d*. The closing of contact *a* of relay XR completes a stick circuit for that relay extending from terminal B at contact *e* of relay OR over the manually operable switch TB, contacts *b* of relays RAK and LAK, contact *a* and the upper winding of relay XR to terminal O, whereby relay XR is held energized after relay 1P releases at the end of the first step.

Assuming now that the received code has progressed to the tenth step and that relays A2 and 10P are picked up; relay TK is energized momentarily in the normal direction over the circuit extending from terminal B at contact *e* of relay A2, contact *b* of relay OR, contact *c* of relay 10P through relay TK and the lower winding of relay XR to terminal O. Relay TK remains in its normal position as shown, and since the currents in the two windings of relay XR are additive, relay XR remains normal.

Similarly, if relay A2 is energized when relay 12P or 14P picks up, the indication relay LAK or RAK being normal, as shown, relay XR also remains normal. If relay LAK or RAK is operated from reverse to normal, relay XR is held energized by the current through its lower winding during the time that the indication relay contact *b* is in transit and the current through the upper winding of relay XR is thereby interrupted, so that in this case as well, relay XR remains normal.

Assuming next that relay C2 is energized in place of relay A2 on the tenth step, relay TK will be operated to reverse over the circuit extending from terminal O through the lower winding of relay XR, the winding of relay TK, contact *c* of relay 10P, contact *b* of relay OR, to terminal C at contact *e* of relay C2, thereby lighting the lamp TKE to indicate that the corresponding track section is occupied. The currents in the two windings of relay XR now are in opposition, but it is to be understood that the circuits are so proportioned that the energization of the upper winding predominates by an amount at least sufficient to overcome the relay bias, or tendency of the relay to close its reverse contacts when deenergized, and to provide sufficient additional energization to maintain the normal contact *a* closed.

If relay C2 is energized when relay 12P or 14P picks up, and the indication relays LAK and RAK already occupy their reverse positions, relay XR will remain in its normal position, for similar reasons. On the other hand, if relay LAK or RAK is initially in its normal position and is operated to reverse, its contact *b* while in transit opens the circuit through the upper winding of relay XR and then the reverse current through the lower winding of relay XR, assisted by its biasing force, drives its contacts to reverse, completing the circuit from terminal B over contacts *f* of relays OR and 1P and contact *d* of relay XR through the winding of the bell XB to terminal C, thereby ringing the bell XB to announce the lighting of an indication lamp in the track diagram.

It may happen that after relay XR has been reversed by one indication relay, such as the relay LAK, another indication relay LAK is operated to normal on a succeeding step which follows so quickly that there is insufficient time for the proper operation of the bell XB between the two steps. For this reason relay XR is arranged to be non-responsive to the code impulses which follow the one by which it is reversed by the clos-

ing of its contact *b* which shunts its lower winding, and as shown, bell XB remains energized until relay OR is released at the end of the code.

It will be seen that the bell XB is caused to sound once during each code by which one or more indication relays are operated from normal to reverse, but under no other condition.

It will be understood that the system generally includes a number of track indication relays like relay TK and that all of these will have their contacts *b* so located in the stick circuit for relay XR that they are shunted by the switch TPB. When switch TPB is open, these relays are rendered effective to operate the bell XB, as will be obvious.

Relay XR may also be of the stick polar type, like the indication relays. It will be clear, however, that the driving force applied to the contacts of relay XR should be considerably in excess of that applied to contacts *b* of the indication relays in order to insure the opening of contact *a* of relay XR even though the time the indication relay contact *b* is open in transit is extremely short. If this force is due solely to the current in the lower winding of relay XR, the indication relays in series therewith would require special windings of low resistance. A biased polar relay is therefore preferred as only a portion of its reverse driving force is obtained from its lower winding, permitting its connection in series with standard indication relays similar to those used elsewhere in the system. Nevertheless, this circuit materially increases the force available for driving the relay to reverse over that obtainable by merely opening the circuit through the upper winding with the relay driven merely by its biasing force which obviously is always less than that obtainable by energizing the relay. Consequently relay XR operates at a relatively high speed, providing proper operation even though the transit time of the indication relay contacts is extremely short.

Although I have herein shown and described only one form of apparatus embodying my invention, it is understood that various changes and modifications may be made therein within the scope of the appended claims without departing from the spirit and scope of my invention.

Having thus described my invention, what I claim is:

1. Annunciating apparatus for audibly indicating a change in condition of any one of a number of visual indicators comprising, an indication relay of the stick polar type controlling each indicator, an additional polar relay having two windings, means for momentarily energizing one winding of the additional relay in the normal direction and then energizing the other winding of said relay in the normal or reverse direction in series successively with each of said indication relays, a holding circuit including said one winding and a normal contact of the additional relay and a contact of each indication relay adapted to open the circuit momentarily when such contact is in transit from one position to another, an audible signal device, and an energizing circuit for said device controlled by a reverse contact of said additional relay.

2. In combination with a series of indication relays operable to normal or reverse positions, a polar relay having two windings, a circuit including one winding of the polar relay for energizing the relay momentarily in the normal or reverse direction whenever one of said indication relays is operated to a corresponding normal or reverse

position, a circuit including the other winding of said polar relay for holding the relay energized only as long as it remains in its normal position including its own normal contact and in series therewith a contact of each indication relay arranged to open the circuit momentarily when such contact is in transit from one position to another, an audible signal device controlled by a reverse contact of said polar relay, and means for operating said polar relay to its normal position to establish said holding circuit.

3. In combination with a series of indication relays operable to normal or reverse positions, a polar relay having two windings, a circuit including one winding of the polar relay for energizing the relay momentarily in the normal or reverse direction whenever one of said indication relays is operated to a corresponding normal or reverse position, a circuit including the other winding of the polar relay arranged to energize the relay in the normal direction only as long as it remains in its normal position and each indication relay remains in its normal or reverse position, and an audible signal device responsive to the closing of a reverse contact of said polar relay.

4. In combination with a series of indication relays of the stick polar type, an additional polar relay having two windings, means for energizing said indication relays successively in the normal or reverse direction in series with one winding of said additional relay, a circuit including the other winding of said additional relay arranged to energize the relay in the normal direction only as long as it remains in its normal position and each indication relay remains in its normal or reverse position, means for short circuiting said one winding of the additional relay comprising a reverse contact of such relay, a signal device, and an energizing circuit for said device including a second reverse contact of said additional relay.

5. In combination with a series of indication relays of the stick polar type, a remote control system for operating said indication relays successively by impulses of normal or reverse polarity, an additional polar relay having two windings one of which is connected in series with said indication relays to render the indication relay responsive to each of said impulses, means including said remote control system for causing said additional relay to assume its normal position prior to the operation of said indication relays, a holding circuit for said additional relay including a normal contact of said additional relay and its other winding, means including a contact of each indication relay for opening said holding circuit momentarily during the operation of such indication relay from one position to another, means including a contact of said additional relay closed in its reverse position for rendering such relay non responsive to the impulses supplied to the indication relays, a signal device, and an energizing circuit for said device including a second reverse contact of said additional relay.

6. In combination with a series of indication relays operable to normal or reverse positions, a polar relay having two windings, means including a series of impulses of selected character for positioning said indication relays successively to normal or reverse as required to correspond with the character of said impulses, means for repeatedly energizing one winding of said polar relay in the normal or reverse direction in accordance with the character of the successive impulses, a circuit

including a normal contact and the other winding of said polar relay arranged to be energized to hold the relay normal even though its one winding is energized in the reverse direction, means including contacts of said indication relays for opening said holding circuit momentarily when any indication relay is operated from one position to another to effect the reversal of the polar relay provided its one winding is energized reverse at the time, means including a second contact of the polar relay for preventing the energization of its one winding after the relay has been reversed, a signal device, and an energizing circuit for said device controlled by said polar relay.

10 7. In combination with a series of indication relays operable to normal or reverse positions, a polar relay having two windings and normally biased to a reverse position, means including a series of impulses of selected character for positioning said indication relays successively to normal or reverse as required to correspond with the character of said impulses, means for repeatedly energizing one winding of said polar relay in the normal or reverse direction in accordance with the character of the successive impulses, a circuit including a normal contact and the other winding of said polar relay arranged to hold the relay normal against its bias and also against the reverse energization of its one winding, means including contacts of said indication relays for opening said holding circuit momentarily when any indication relay is operated from one position to another to effect the reversal of the polar relay provided its one winding is energized reverse at the time, means including a contact of the polar relay for preventing the energization of its one winding after the relay has been reversed, a signal device, and an energizing circuit for said device controlled by the polar relay.

15 8. In combination, a series of indication relays, a polar relay biased to a reverse position, a normally closed holding circuit for the polar relay including a normal contact of said relay and contacts of said indication relays each adapted to open the circuit when in transit from one position to another, means including a second circuit for energizing the polar relay in the normal direction to prevent its reversal during the time said holding circuit is opened due to the movement of any indication relay contact to a given position and for energizing the polar relay in its reverse direction to increase the force acting to reverse the relay when its holding circuit is opened due to the movement of any indication relay contact to its other position, a signal device, and means responsive to the reversal of said polar relay for actuating said signal device.

15 9. In combination, a series of indication relays, a two position polar relay, a normally closed holding circuit for the polar relay including a normal contact of said relay and contacts of said indication relays each adapted to open the circuit when in transit from one position to another, means including a second circuit for energizing the polar relay in the normal direction while said holding circuit is opened due to the movement of any indication relay contact to a given position and for energizing the polar relay in the reverse direction to effect its reversal while said holding circuit is opened due to the movement of any indication relay contact to its other position, a signal device, and means responsive to the reversal of said polar relay for actuating said signal device.
